(57) **CLAIM**

The ornamental design for a circular light, as shown and described.

DESCRIPTION

FIG. 1 is a perspective view of a circular light showing a first embodiment of my new design, as viewed from the top and front.

FIG. 2 is a top plan view thereof.

FIG. 3 is a bottom plan view thereof.

FIG. 4 is a front profile view thereof.

FIG. 5 is a back profile view thereof.

FIG. 6 is a first side profile view thereof.

FIG. 7 is an opposite second profile view thereof.

FIG. 8 is a perspective view of a circular light showing a second embodiment of my new design, as viewed from the top and front.

FIG. 9 is a top plan view thereof.

FIG. 10 is a bottom plan view thereof.

FIG. 11 is a front profile view thereof.

FIG. 12 is a back profile view thereof.

FIG. 13 is a first side profile view thereof; and,

FIG. 14 is an opposite second profile view thereof.

The details shown in broken lines illustrate features that form no part of the claimed design.
